UNITED STATES PATENT OFFICE.

VALENTINE O. ZAHNISER, OF WASHINGTON, PENNSYLVANIA.

BULL-WHEEL.

1,143,012.

Specification of Letters Patent. Patented June 15, 1915.

Application filed June 4, 1914. Serial No. 842,993.

To all whom it may concern:

Be it known that I, VALENTINE O. ZAHNISER, a citizen of the United States, residing at Washington, in the county of Washington and State of Pennsylvania, have invented certain new and useful Improvements in Bull-Wheels; and I do declare the following to be a full, clear, and exact description of the invention, such as will enable others skilled in the art to which it appertains to make and use the same.

This invention relates to the art of oil and Artesian well drilling and more particularly to the bull wheels employed for raising and lowering the tools. Wheels of this character are ordinarily journaled to rotate freely upon the sills of a well boring derrick or in close proximity thereto, are equipped with the usual bull rope or ropes and drilling cable, and are periodically driven by the bull rope for the purpose of coiling or reeling the drilling cable.

The object of this invention is to provide improved means for attaching the wheels to the shaft or coiling drum and to improve the general construction of the wheel.

With the above and other objects in view, the invention consists of certain novel features of construction, combination and arrangement of parts as will be more fully described and claimed.

In the accompanying drawings: Figure 1 represents a side elevation of this improved bull wheel with parts broken out; Fig. 2 is a transverse section taken on line 2—2 of Fig. 1; Fig. 3 is a similar view taken substantially on the line 3—3 of Fig. 1; Fig. 4 is a transverse vertical section of the tug wheel taken on line 4—4 of Fig. 3; Fig. 5 is a detail front elevation of one of the spokes with one of the cant connecting sockets arranged in juxtaposition ready for engagement therewith; and Fig. 6 is a detail vertical transverse section showing a slightly modified form of tug wheel.

In the embodiment illustrated, a main shaft or coiling drum 1 is shown composed of a pipe having gudgeons 2 shrunken into the ends thereof and which are designed to rotatably support the wheel in supports not shown. Fixed to one end of said drum 1 is a driving or tug wheel 3 which comprises a hub 4 and spokes 5 composed of a plurality of sections or members 6, each constructed of flat steel bars, and four being here shown.

Each member 6 is substantially U-shaped as shown in Fig. 5 and each comprises an arcuate section or segment of the hub and two arms or spoke members. Each of these U-shaped members 6 has the arcuate cross bar 60 7 thereof curved inwardly to conform to the curvature of the pipe 1 to which it is to be applied to form a hub section. The inner portion of the arm on each end of each bar 7 is inclined outwardly as shown at 8 and 65 apertured to receive bolts for connecting them with adjacent members and the curved portions 7 thereof are also apertured for the passage of the bolts 9 which secure said members to the pipe or drum 1. 70

The outer or body portions 10 of the arms of the members 6 preferably diverge slightly and the terminals 11 thereof are inclined slightly outward. Four of these members 6 are here shown which when assembled, in 75 operative position on the drum 1, have their inclined arm portions 8 positioned in close contact to form reinforced spoke members and which are secured together by bolts or other suitable fastening elements. When 80 these members are so secured, the arms 10 of adjacent members diverge and form Y-shaped spokes with V-shaped spaces 10' between the outer ends thereof. By this arrangement four Y-shaped spokes 5 are provided to the free ends of which are secured peripherally grooved cants 12 which are 85 preferably composed of wood and are secured to connecting members 13 mounted on the ends of said spokes. The members 90 include laterally disposed apertured plates 13^a and 13^b which extend in opposite directions from the outer ends of the body portions 13 and are designed to be secured to the inner faces of the cants 12 by bolts or 95 screws which pass through the apertures in said plates 13^a and 13^b and enter said cants. The members 13 fit over the free ends of the arms 10 and are secured thereto in any suitable manner, bolts being here shown for this 100 purpose. When these cants 12 are assembled, the grooves in the working faces thereof provide a continuous rope groove 14 for the reception of the bull rope (not shown). In the form shown in Figs. 1 to 5, one bull 105 rope groove is illustrated while in Fig. 6, two grooves are shown. Arranged on opposite sides of the cants 12, when the latter are assembled, are annular clamping plates 17 and 18, each preferably composed of seg- 110

ments of greater width than the cants 12 and which have their outer or peripheral edges arranged flush with the outer faces of the cants and extend at their inner edges 5 beyond the inner edges of the cants and over the sockets 13 completely housing said inner cant edges and said sockets and thereby protecting them. These plates 17 and 18 are secured in operative position by bolts 10 or rivets 19 which pass transversely through the plates at opposite sides of the wheel and through the cants disposed between them.

In the form shown in Fig. 6, the cants 12' have two parallel peripheral grooves 14' 14'' 15 to receive two bull ropes. Otherwise, the construction of this form of rim is the same as that in the other figures.

This wheel is preferably secured to the shaft 1 by passing the bolts 9 diagonally 20 through said shaft so that each bolt passes through two diametrically disposed hub sections 7 and which reliably and securely fasten the wheel to the shaft. Secured to the other end of the shaft 1 is a brake wheel 15, the construction of which is similar to that of the tug wheel with the exception that plain cants are used for forming the rim instead of grooved cants and on which is designed to be mounted a brake 25 band for controlling the unwinding of the drilling cable.

Projecting from the rim of the tug or drive wheel 3 preferably on the inside and from the rim of the brake wheel preferably 35 on the outside, are a plurality of pins 16 and 16' respectively for use in manually rotating said wheels when desired. The pins 16 are employed for rotating the drive wheel 40 when the bull rope has been thrown off or requires replacing and the pins 16' for ro-

tating the brake wheel when the brake band is out of operation.

In the use of this bull wheel which is located adjacent to a stationary engine or other source of power, motion is imparted 45 to the drive wheel 3 when required by means of a bull rope thrown into the groove 14 whereby said wheel is rotated in the usual manner. The drill rope will then be rapidly coiled upon the drum 1 thus elevating the 50 drill or other tool quickly from a well.

When it is desired to return the same tool or another into the well, the drum 1 will unreel under the weight of the tool carried by the end of the drill rope and said rope and tool are held in check by a suitable band or other form of brake applied to the surface 55 of the brake wheel 15.

I claim as my invention:

A pulley wheel for well rigs comprising a 60 rim, a plurality of substantially U-shaped sections with rim engaging means at the outer ends of their arms, each arm projecting radially inward from the rim a short 65 distance and then obliquely outward from the radius, but in the same plane therewith until contacting with the arm of its adjacent section, and from which point of contact radially inward and parallel with the 70 said contacting arm to a plurality of arcuate hub engaging members forming the base of said U-shaped sections, and means for securing the adjacent parallel arms together.

In testimony whereof I have hereunto set my hand in presence of two subscribing witnesses. 75

VALENTINE O. ZAHNISER.
